UNITED STATES PATENT OFFICE.

ALONZO LEVI HOOK, OF COFFEYVILLE, KANSAS, ASSIGNOR OF TWO-THIRDS
TO JAMES ROBERT HUTTON, ROSCO KIRBY LONG, AND ROBERT LINCOLN
PLUNKETT, OF COFFEYVILLE, KANSAS.

GRAIN-CAR DOOR.

SPECIFICATION forming part of Letters Patent No. 709,325, dated September 16, 1902.

Application filed May 2, 1902. Serial No. 105,624. (No model.)

To all whom it may concern:

Be it known that I, ALONZO LEVI HOOK, a citizen of the United States, and a resident of Coffeyville, in the county of Montgomery and

5 State of Kansas, have invented certain new and useful Improvements in Grain-Car Doors, of which the following is a specification.

My invention relates to doors for grain-cars, and it appertains to doors of this character held in slideways and adapted to be lifted therein with suitable mechanism supported above the door and also adapted to be raised above the slideways and swung up to the top of the car, where it may be supported 15 by a hook or other device, all as is common and well known.

The invention consists in a special door and special means for lifting it, all as will be hereinafter fully described, with the novel 20 features pointed out in the claim.

In order to enable others to make and use my invention, I will now proceed to describe it in detail, reference being had to the accompanying drawings, which form a part of this 25 specification, and in which—

Figure 1 is a view showing a section of a car with the door lowered and fastened as in use. Fig. 2 is an interior view of the same. Fig. 3 is a section on line xx of Fig. 2. Fig. 30 4 is an enlarged detail view showing the lever-and-ratchet mechanism, and Fig. 5 is a perspective view showing the slideway and shaft-supporting bracket of one side of the door.

35 I am aware that a door for grain-cars consisting of two parts hinged together is not broadly new, and I am also aware that various means have been employed for lifting the door and also that such doors have been 40 arranged to slide in guideways.

What I claim as my invention is the new and improved grain-door for cars, which I will now proceed to describe in detail as follows:

45 In carrying out my invention I employ a door A, having hinged to its upper edge a reduced door B. D indicates castings secured to the inner side of the car-framing or stanchions, forming side members of the door opening. The castings D are formed with

guideways E in length about equal with the width of the door A and in which the door is adapted to slide. The side edges of the doors A and B are protected with metal strip A'. (See Fig. 2.) F indicates brackets projecting 55 from the castings G, which latter, with the castings D, extend the whole length of the stanchions above mentioned and are secured thereto by screws, bolts, or other suitable means. The castings D and G at both sides 60 of the door are tongue-and-grooved together. (See Fig. 5.) With side castings formed in two parts it is apparent the upper casting, carrying the brackets F, may be adjusted to provide support for the shaft H at varying 65 heights. Advantage is had in fitting the abutting ends of the said castings D and G together by a tongue-and-groove joint, since should it become necessary to adjust one or both of the castings G for setting the shaft- 70 supporting brackets F in alinement or to slight elevated position adapted for proper support of the shaft H the said adjustment of the upper casting may be made and still leave the stanchions with a substantially un- 75 broken metal facing—that is, should the adjustment described not carry the lower end of the tongue on the casting G out of the groove or socket in the upper end of the casting D.

The brackets F provide support for the shaft H, arranged above the door-opening in the car and on the inside thereof, as shown. One end of the shaft H outside the bucket is provided with a head I, and on the other end 85 of said shaft I arrange a toothed or ratchet wheel J, straddled by the forked members of a lever K. Between the said forked members is pivoted a weighted dog L, with its shorter end engaging the teeth of the ratchet-wheel 90 J. Above the said ratchet-wheel J and secured to the side of the car I arrange a pawl M, having engagement therewith to prevent reverse rotation of the ratchet-wheel. From the shaft H depend chains whose lower ends 95 connect loops or eyes at the upper edge of the door A. (See Figs. 1 and 2.) On the outside of the door A, I arrange sliding bolts N, adapted for engagement with recesses in the stanchions or side members of the door. The 100

bolts N are worked by cam-levers O for locking the door A against moving upwardly. The reduced or hinged door B is secured in an upright position by hooks and eyes P. At 5 the threshold of the opening in the car and in front of the door A may be arranged and secured a bar R to resist outward pressure of grain.

With the above detail description of my 10 invention it becomes necessary only to say that in use with a car loaded with grain and both doors secured when it is desired to unload the car the hooks P are first disengaged, when the hinged door may be turned inwardly. With the door B turned as stated 15 an unloader may enter the car and by working the lever K wind the door - elevating chains on the shaft H. The lower end of the said chains being fast to the upper edge of 20 the door A, it is apparent that the latter may be raised in the guideways by working the lever, as stated above, and that with the doors raised grain will pass out through the opening provided fast or slowly, according to the 25 elevation of the lower door in the guideways. When a car is unloaded, the door may be raised until free of its guideways and then 30 swung inwardly up to the top or roof of the car and be secured in such position by a hook or other desired means.

Having thus fully described my invention, what I claim as new, and desire to secure by Letters Patent, is—

The combination with a car-door adapted to be elevated, means for guiding the door 35 and manually-operated means adapted to be worked for elevating the door, of peculiar guideways for the door and peculiar support for the said elevating means, the said guideways consisting of castings having in addition to means for guiding the door, a groove or socket at their upper ends, and the support for the elevating means consisting of castings having a tongue at their lower ends adapted to enter and fit a socket at the upper end of the lower casting and integral brackets providing support for the winding-shaft, chains leading therefrom with fixed connection to the door and also the means for working said shaft, a ratchet-wheel on the 40 shaft, a lever having pivotal movement on the shaft and carrying a weighted dog having slipping movement from tooth to tooth of the ratchet-wheel, and a fixed pawl operating to hold the shaft as wound, substantially as de- 45 scribed.

ALONZO LEVI HOOK.
